UNITED STATES PATENT OFFICE.

HARRISON W. MYERS, OF FREEPORT, NEW YORK.

COMBINED ENVELOPE AND INVOICE SHEET.

Application filed June 3, 1928. Serial No. 113,400.

My present invention relates to commercial forms and particularly to those which require a reply with an enclosure or remittance, such as bills or statements of account.

5 It has for an object the provision of a blank adapted to be employed both by a creditor as a form for rendering a statement of account and by the debtor as an envelope for enclosing a reply to or remittance in payment of the 10 statement.

Another object of my invention is the provision of a commercial form of such construction as to provide the creditor with a means of positively and readily identifying an account for which a remittance has been received.

Briefly stated these objects are accomplished by the provision of a sheet or blank comprising an end portion to receive the bill or letter-head and a body portion adapted to receive the items of account and to be folded upon the upper portion for mailing, the end portion having end and side flaps, preferably gummed, which are sealable over the folded form to produce an envelope for return mailing. The reverse side of the end portion is preferably provided with directions for locating the creditor, thereby providing a convenient form for use by the debtor or in enclosing a remittance to a statement and at the same time furnishing the creditor with a positive or definite identification of the account.

The invention will be more thoroughly understood with the aid of the description to be given in connection with the following drawings in which:

Fig. 1 is a view of a statement blank formed in accordance with the invention and folded ready for insertion in an envelope.

Fig. 2 is a perspective view from the rear of the blank shown in Fig. 1.

Fig. 3 is a base view of the same blank form unfolded.

45 Fig. 4 is a rear view of the form as shown in Fig. 3.

Figs. 5 and 6 are views of opposite sides of the form folded ready for return as an envelope.

50 In the drawings the same reference characters have been employed to denote similar parts.

Referring to the drawings, there is shown a blank bill or statement form printed on a 55 suitable sheet of paper, the face thereof dis-

playing the usual body portion 7, ruled and lettered as desired to receive the itemization or statement of account proper, and having an end portion 8 adapted to receive the usual letter or bill-head. When employed by a 60 creditor in rendering a statement of account, the form represented herein is not folded in the customary manner, but rather as shown in Fig. 2 so that the end portion 8 containing the customer's name and address is outermost so that when inserted in an envelope having a cut-out portion in its face or an area therein which has been treated to render it transparent, the name and address is visible, thereby obviating the necessity of addressing the envelope separately, as shown in the dot-and-dash lines in Fig. 1.

In the preferred form of my invention, the end portion 8 of the above described form is provided with end flaps 9—9, and a side flap 10, which flaps are preferably gummed. With the addition of these flaps, the blank received by a customer or creditor may be readily employed as a return envelope serving as an enclosure for a reply to or remittance in 80 payment of the statement, the blank being folded in the manner shown in Figs. 5 and 6 with the reverse side of the top portion 9 outward and with the flaps 9—9 and 10 folded over and sealed to the folded body portion 8. 85 With a form of commercial statement arranged as described, a dual advantage is present because not only is the debtor furnished with a ready and convenient means for making reply to the statement, but the creditor is also provided with a positive means of identifying the particular account upon receipt of the envelope, as the statement per se containing the customer's name and address is returned with the remittance.

90 In mailing the statement to the customer, it is preferably folded as shown in Fig. 2, with the top or end portion 8 outward, the flaps 9—9 and 10 being turned back to cover or to be covered by, as desired, the folded body portion 7. When so folded the form may quickly be turned into an envelope by the debtor by reversing the original creases or folds and affixing the flaps to form a sealed form. For further convenience and assurance of return, the creditor's name may be printed as indicated in Fig. 6 on the face of the return envelope which in reality is the reverse of the top portion 8.

Some suitable means of directing the debt- 110

or's attention to the new use which may be made of the form and instructing him in its use is preferably provided. To the accomplishment of this end, I have found the use 5 of a short printed notice at the bottom of the top portion 8 directing attention to the use of the statement as a return envelope, in combination with a system of numerals and directions at each crease or fold to be a satisfactory arrangement.

In order to facilitate the folding of the form into a return envelope, as shown in Figs. 5 and 6, the longitudinal edges of the body portion 7 are preferably given a slight taper, 10 as shown.

In the improved form of statement which my invention provides there are combined with all the essential functions of the ordinary statement means by which the creditor 20 will have increased assurance of possessing a definite identification of the account when settled by mail and by which the debtor will be provided with a ready and convenient return envelope form.

In addition to the various uses above outlined, my new form is especially adapted for use by commercial houses, insurance companies, public service corporations and the like, in advising or notifying debtors of the amount 30 due, such as is the case with premiums and insurance policies.

In accordance with the provisions of the patent statutes the principle of the invention has been described, together with the apparatus 35 which is now considered to represent the best embodiment thereof, but it is desired to have it understood that the apparatus shown is merely illustrative, and that the invention may be carried out in other ways.

The invention having been described, what 40 is claimed as new and desired to be secured by Letters Patent, is as follows:

1. A commercial bill sheet having the usual bill set up and foldable transversely on spaced 45 lines of fold, the top panel of the sheet formed by said folding bearing on its inner face, the creditor's designation to the debtor located at the upper portion of said panel and below

the same a space to receive the debtor's name and address in position to register with the window area of an enclosing envelope in which the blank is enclosed when folded with the space so filled in exposed, said panel on its opposite side bearing the name and address of the creditor for return mailing purposes, said bill sheet being reversibly foldable on said lines of fold to alternately lie against the opposite faces of said top panel, sealing flaps on the lateral and top edges of said panel, each having gummed portions on that side of the sheet bearing billing indicia and cooperating with that portion of the sheet when folded upon the inner face of the panel to seal the same with the creditor's address exposed upon the outer face of the panel.

2. A commercial form mailing sheet comprising a sheet having a panel portion provided with foldable top and end sealing flaps and a foldable sheet portion extending from the bottom thereof, said panel having on one face an addressee's designation positioned to register with the window area of an enclosing envelope, the other face of said panel having the addressor's designation positioned thereon for returned mailing purposes, said lower sheet portion being foldable to a position covering the face containing the addressor's remailing indicia, and to retain the sealing flaps when said flaps are folded against said face, so that said flaps may be temporarily confined to facilitate insertion of the sheet in said enclosing envelope with the addressee's designation in position to be exposed through the window thereof, said sheet portion being reversely foldable to cover the other face of said panel bearing the addressee's designation so that the sealing flaps may be folded over and secured to the folded sheet to retain it in sealed condition and to expose the face containing the addressor's remailing indicia, whereby said sheet is in condition for remailing.

This specification signed and witnessed this second day of June, 1926.

HARRISON W. MYERS.
